Primary Examiner — Susan Bennett Hattan*Assistant Examiner* — Brett Miller(74) *Attorney, Agent, or Firm* — Thomas C. Feix(57) **CLAIM**

The ornamental design for a water bottle top, as shown and described.

DESCRIPTION

FIG. 1 is a perspective view of a top for a water bottle of the present invention;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines depict portions of the article that form no part of the claimed design.
